UNITED STATES PATENT OFFICE.

IRVING R. PRENTISS, OF SCHENECTADY, NEW YORK, ASSIGNOR TO THE GENERAL ELECTRIC COMPANY, OF NEW YORK.

ARC-LAMP.

SPECIFICATION forming part of Letters Patent No. 637,825, dated November 28, 1899.

Application filed August 12, 1899. Serial No. 726,980. (No model.)

To all whom it may concern:

Be it known that I, IRVING R. PRENTISS, a citizen of the United States, residing at Schenectady, county of Schenectady, State of New York, have invented certain new and useful Improvements in Arc-Lamps, (Case No. 945,) of which the following is a specification.

The object of this invention is to provide an arc-lamp which may be set to run at determined hours and in which a record will be preserved of the number of hours of service. I provide means for effecting these results.

In carrying out the invention I provide a clockwork, controlled by the operation of the lamp, released so as to run during the time the arc is burning and automatically arrested when the arc is extinguished. I provide also automatic winding arrangements for the time-train controlled by the operation of the lamp, so as to keep the indicator always ready for action. I provide also means by which the lamp can be burned only for a definite number of hours, after which it will be automatically cut out of action.

My invention therefore comprises an arc-lamp, in combination with means for preserving a record of the time during which the lamp is in service.

More specifically, it comprises a wheel-train and register, combined with the lamp, and mechanical connections with the lamp for releasing the wheel-train when the arc is burning and for automatically storing power from time to time in the driving mechanism for the wheel-train.

It comprises also means for predetermining the period in hours during which the lamp shall burn, so that the lamp may be lighted for any desired fractional part of the life of its carbon.

Other features of novelty will be hereinafter more specifically pointed out, and will be definitely indicated in the claims.

In the drawings, Figure 1 is a sectional view of the feed mechanism of a lamp embodying my improvements. Fig. 2 is an elevation of the wheel-train and registering device, broken away in parts to more clearly exhibit the mechanism. Figs. 3 and 4 are detail views of

controlling devices limiting the time of operation of the lamp.

My invention is applicable to any type of arc-lamp. In the drawings I have shown it as combined with a constant-potential type of inclosed arc-lamp, the connections of which will be only sufficiently referred to to indicate the operative relation of the parts, as any type of lamp in which the carbons are periodically fed may be employed.

1 represents a clutch for the positive electrode, controlled by the core 2 of a series coil 3.

4 is a dash-pot for damping the movements of the core of the regulating-coil, and 5 a supporting-spring for carrying the weight of the parts. Connected to the rod between the clutch and the core of the regulating mechanism is a lever 6, pivoted to the frame of the lamp at one side and carrying the pivoted rod 7, to the top of which is secured a brake 8 in operative relation to the rim of the balance-wheel of a clock-movement. The latter may be of any ordinary construction and is so mounted in the lamp that a door in the casing may be opened to give access to the clock for adjustment or examination. The brake-shoe 8 and the rod on which it is mounted are so arranged that the shoe is in engagement with the balance-wheel of the clock-movement when the lamp is not burning, and when the arc is struck the shoe is removed from the balance-wheel, permitting the clock to run. The rod which carries the brake-shoe is also provided with a pawl 9, engaging a ratchet-wheel secured to the spring-barrel which drives the clock-train, so that when the lamp feeds the motion imparted to the magnet-core to effect such feed will increase the tension of the clock-spring by pushing forward the pawl 9. Thus the clock may be kept continuously wound by the intermittent efforts of the lamp when feeding.

On suitable arbors of the clock-train are provided indicators 10 11, moving over dials to indicate the hours and days the lamp is operated. The wheelwork may be mounted in the casing of the lamp mechanism so that the dials lie behind glazed openings 12 13, permitting the lamp-register to be read or inspected read-

ily. The clock-train should be provided also with a winding-post accessible from a door in the lamp-frame for winding the clock when necessary, and especially when the lamp is initially operated.

On the hour-post of the clock I provide a device for determining the length of time the lamp may be used. The details of this organization are shown in Figs. 2 and 3. It comprises a semicircular disk 14, which is mounted friction-tight on the arbor, but is capable of being turned by means of knobs 16, accessible from the outside of the mechanism. A small dial may be mounted on the movable disk to indicate relatively to the hour-dial the length of time the lamp is to burn and permit it to be set for any definite hour. The disk may be set so as to bring a notch 15^a any desired angular distance from a zero-point ("0") on the clock-face, the angular distance being read in hours on the small dial 15, as indicated, the notch being provided with a curved edge, as shown at 15^a. Adapted to bear on the periphery of the disk is a roller 18, connected to a spring-controlled lever 19, which carries two contacts adapted to engage two corresponding fixed contacts connected to the lamp-terminals, and thereby short-circuit the lamp, or otherwise arranged to cut it out of service.

It will be evident from an inspection of the drawings that the length of time during which the lamp is in action is governed by the length of the arc between the notch 15^a and the zero-point, ("0,") which may be adjusted to any number of hours desired, from one to twenty-four. The dials on the clock may be arranged to cover any desired period of operation of the lamp. As shown, it provides a register for a month, during which period the lamp should be inspected and reset. When the lamp is adjusted to burn for a definite number of hours per day, the trimmer should reset the dial at the end of the run, as the lamp is cut out of circuit until the notch 15^a is again moved away from roller 18. The door by

which access is gained to the registering mechanism is of course kept under lock and key and accessible only to an employee of the supply company.

What I claim as new, and desire to secure by Letters Patent of the United States, is—

1. An arc-lamp provided with a register to indicate the term of its service, and means controlled by the feeding mechanism of the lamp for operating such register.

2. An arc-lamp provided with a time-train operated by the feeding mechanism of the lamp, and means for setting said time-train for any period of operation of the lamp.

3. An arc-lamp provided with a clock-train, a register operated thereby, means for releasing the clock-train when the lamp is burning and arresting it when the lamp is extinguished, and means for periodically automatically winding the clock-train.

4. An arc-lamp provided with a clock-train, a register operated thereby, means for releasing the clock-train when the lamp is burning, and winding mechanism for the clock-train periodically operated by the lamp mechanism.

5. An arc-lamp provided with a clock-train, a register operated thereby, means for releasing the clock-train when the lamp is burning and arresting it when the arc is extinguished, and a winding device for the clock-train connected to and operated by the feed-regulator of the lamp.

6. An arc-lamp provided with a wheel-train, means for releasing the same by the action of the lamp while burning, and setting devices for extinguishing the lamp after a determinate period of movement of the wheel-train.

In witness whereof I have hereunto set my hand this 9th day of August, 1899.

IRVING R. PRENTISS.
